DESIGN FOR A GAME BOARD

Max H. Silverman, New York, N. Y.

Application February 27, 1947, Serial No. 137,199

Term of patent 3½ years

(Cl. D34—5)

To all whom it may concern:

Be it known that I, Max H. Silverman, a citizen of the United States, and a resident of 1515 Metropolitan Avenue, county of Bronx, city and State of New York, have invented a new, original, and ornamental Design for a Game Board, of which the following is a specification, reference being had to the accompanying drawing, forming a part thereof.

On the drawing:

Figure 1 is a top plan view of the game board, showing my new design.

Figure 2 is an end view in elevation broken away from Figure 1.

The line shading is adapted to designate contrasting colors.

I claim:

The ornamental design for a game board, as shown and described.

MAX H. SILVERMAN.
